UNITED STATES PATENT OFFICE

142,604

DESIGN FOR A SIGN SUPPORTING BRACKET

Vernon Werkmeister, Villa Park, Ill., assignor to Schneider Metal Manufacturing Company,
Chicago, Ill., a corporation of Illinois

Application January 10, 1945, Serial No. 117,365

Term of patent 7 years

(Cl. D1—12)

To all whom it may concern:

Be it known that I, Vernon Werkmeister, a citizen of the United States, residing in Villa Park, in the county of Cook, State of Illinois, have invented a new, original, and ornamental Design for a Sign Supporting Bracket, of which the following is a specification, reference being had to the accompanying drawing, forming part thereof.

The single figure of the drawing is a perspective view of a sign supporting bracket showing my new design.

I claim:

The ornamental design for a sign supporting bracket, substantially as shown.

VERNON WERKMEISTER.
